UNITED STATES PATENT OFFICE.

WILLIAM GILLIES ROSS AND DUNCAN McDONALD, OF MONTREAL, QUEBEC, CANADA.

PASSENGER-CAR.

No. 875,740.

Specification of Letters Patent.

Patented Jan. 7, 1908.

Application filed July 26, 1907. Serial No. 385,619.

To all whom it may concern:

Be it known that we, WILLIAM G. ROSS and DUNCAN McDONALD, both subjects of His Majesty the King of Great Britain and 5 Ireland, residing at Montreal, Province of Quebec, Dominion of Canada, have invented certain new and useful Improvements in Passenger-Cars, of which the following is a specification.

- 10 The car is divided into two or more compartments, each of the compartments having an exit and a common entrance for the several compartments, the entrance and exits being on the side of the car instead of at the 15 ends, as is customary in prior constructions.
- 15 The car is particularly advantageous as an observation car, with a clear, unobstructed view for the passengers at either end and to increase the advantages of this feature, the 20 motorman's platform is sunk below the level of the floor of the car and at one side of the front thereof, so that by making the inclosure of glass, at least the upper part, there is a clear vision for passengers in the car.
- 25 The car is adapted to be made of greater width than is now permitted in street car service, and to accommodate this, the center of the car is offset from the running gear or trucks at one side so that cars passing each 30 other on parallel tracks and on curves will have the same distance between them as is now allowed, and the additional width of the car extends beyond the running gear on the side opposite the parallel track.
- 35 The principal object of our car is to improve the means of collecting fares from passengers before they enter the compartments of the car, thus making it what is known as a pay-as-you-enter car.
- 40 By providing a space on the platform in the side of the car for passengers with an entrance connected thereto from which the passengers may enter either of the compartments of the car, and by providing a plurality of exits opening from the several compartments, together with the necessary means for directing the passengers so as not to confuse the passage into and out of the several passageways, the efficiency of such car is materially increased. In such a construction, 45 the conductor remains at all times at a point near the entrance door so that he can collect fares and from this position he can signal the motorman upon the exit or entrance of a passenger, which will be near him and in full view of him so that he can give proper attention
- 50 to the running of his car at all times. Heretofore it has been necessary for the conductor to divide his attention between the entering and leaving of passengers on the platform and the collection of fares and it is the disadvantages of such a car which it is our intention to overcome.
- 55 The details of construction and the advantages of our device will be more fully pointed out in the description hereafter.

In the drawings forming part of this application, Figure 1 is a side elevation of a railway car made in accordance with our invention. Fig. 2 is a longitudinal section of the same. Fig. 3 is an enlarged side elevation showing the passenger platform. Fig. 4 is a longitudinal section of the same. Fig. 5 is a section showing the motorman's compartment, and Fig. 6 is a perspective view showing one way of dropping the motorman's compartment below the plane of the car floor. Fig. 7 is a longitudinal section showing a modified form.

As far as our invention is concerned in its broadest aspect, the car may be made with but one compartment divided by a platform projecting within the lateral limits of the car and which is provided with various entrance and exit doors, but there are greater advantages to be had in a car like that shown in the drawings in which the car is divided into two separate compartments, one of which may be used as a smoking compartment.

In the drawings forming part of this application, numeral 1 represents the body of a railway car in which the ends 2 and 3 are closed so that passengers neither enter nor leave from the end platforms, the ends in this car having a free and unobstructed view. Seats 4 are provided in the interior of the car which may run cross-wise in the car or longitudinally, as desired.

As will be seen by reference to the plan view, Fig. 2, the center line 5 of the car is to one side of the center line 6 of the trucks 7, which are shown in dotted lines. In this manner the width of the car on one side of the running gear may be increased without decreasing the clearance space between two cars running on parallel tracks. This is particularly advantageous in a car of the character here shown, where it is preferable to increase the lateral dimensions of the car. Where cross seats are used, sometimes the matter of an inch or two is very important to the seating capacity of the various seats,

The car here shown is divided into two compartments 8 and 9, the former being somewhat smaller than the latter, although the relative sizes may be varied as desired. The compartments are separated by the platform and its surrounding casing and swinging door 10. The platform 11 projects within the lateral limits of the car and towards one side of the car and is provided with the necessary number of steps 12 for the ingress and egress of passengers. In this form of car, it is intended that all passengers enter and leave the car by way of the platform at the side. The platform extends a greater portion of the width of the car leaving a space 13 between its farther side and the side of the car nearest thereto so that a passageway is provided interiorly connecting the two compartments of the car, with the door 10 serving to shut off the smoking compartment from the other compartment. The platform is bounded as follows:—At the ends there are casings 14 and 15 projecting inwardly from the sides of the car which are formed in the nature of walls preferably having pockets 16 and 17 adapted to receive the sliding doors 18 and 19 respectively, which doors form the exits for the compartments 8 and 9 so that passengers may pass out from either compartment without interfering with the entering passengers, as will be seen hereafter. On either side of the platform curved walls or casings 20 and 21 are provided, extending from the edges of the doors 18 and 19 inward and then longitudinal where their opposing ends are connected by the sliding door 22 which is adapted to be received in the pocket 23 of the casing 21. The motorman's box or compartment is at the front and side of the car and has a floor 31 supported by suitable crossings from the lower edges of the sills 30 and 29 and crossing 28. This construction places the motorman where he will interfere with the views of passengers as little as possible. The several elements thus described constitute a substantial rectangular inclosure for the platform separating it from the remainder of the car.

On the platform we provide proper means for diverting the passengers so that those entering the car will be separate from those leaving the car, and in this instance the means consists of a rail 24 extending from the wall 21 in a curved position and running out beyond the edge of the platform and extending over one or more of the steps of the car; and another railing 25 extending from the wall 20 in a similar way and projecting in like manner over the steps, so that there is provided an entrance space between the rails 24 and 25 that passengers may enter by way of the steps to the platform 11 and after paying the conductor who stands within the dividing rail 26, they pass through door 22 and disperse in the several compartments of

the car. Those desiring to go into the compartment A, pass through the swinging door 10; the passengers desiring to leave the car, pass from the compartment 9 through the door 19 which may slide into the pocket 17, or from compartment 8, through the door 18 which is slideable in the pocket 16. The step of the car may be marked to indicate the entrance and exits. As the conductor is at all times on the platform, he is in full control of the movement of the passengers.

In the form shown in Fig. 7 the railings 24 and 25, and steps 12 remain the same. Doorways 18^a and 19^a correspond to the previously described doorways. In this form the passage-way connecting the two compartments is defined by the two railings 39 and 40, with a place of entrance between them. Doorways 42 and 43 open to the several compartments from the passage-way. A railing 41 placed in the passage-way and opposite the entrance defines a place for the conductor to stand and receive the fares from the ingoing passengers.

Various changes may be made in the detail of construction and the arrangement of the parts without departing from the spirit or scope of the following claims:

Having described our invention, what we claim is:—

1. A passenger car having a platform extending inwardly from one side of the car, provided with inclosing means whereby the interior of the car is divided into compartments, said car being provided with an interior passage-way between the platform inclosure and one side of the car whereby the said several compartments are connected.

2. In a passenger car, a platform extending inwardly from one side of the car, and dividing the interior of said car into compartments, the car being provided with a passageway connecting the compartments, an entrance and exit door and means forming separate passageways for the entrance and exit of passengers to and from said entrance and exit doors.

3. A passenger car having a platform extending inwardly from one side of the car, dividing the car into compartments, the car being provided with a passage-way connecting the compartments so formed, an entrance door from the platform into the said passage-way, and exit doors for each of the said compartments and means forming separate passageways for said entrance and exits.

4. A passenger car having a platform extending inwardly from one side of the car, dividing the car into compartments, the car being provided with a passage connecting the compartments so formed, an entrance door from the platform into the said passage and exit doors from each of the said compartments to the said platform.

5. A passenger car having a platform ex-

tending inwardly from one side of the car, steps leading thereto, hand-rails dividing the platform into three ways, and entrance and exit doors from the said platform opening into the three ways.

6. A passenger car having a platform extending inwardly from one side of the car dividing the car into compartments, the car having a passage-way between the said 10 platform and one side of the car, an entrance door from the platform to the said passage-way, exit doors from the compartments to the platform, and means for dividing the platform into three ways.
- 15 7. A passenger car having a platform extending inwardly from the side of the car dividing the car into compartments, steps leading thereto, the car having a passage-way connecting the compartments of the 20 car; an entrance door from the platform to the passage, exit doors from each compartment to the platform, and means for dividing the platform and steps into three ways.
8. A passenger car having a platform extending inwardly from the side of the car thus dividing the car into compartments, steps leading to the platform, an entrance door from the platform to the interior of the 25 car, exit doors from the compartments to the platform, and means for dividing the steps and platform into three ways one of which leads to the entrance door and the other from the exit doors.
9. A passenger car having a platform extending inwardly from the side of the car 30

thus dividing the car into compartments, steps leading to the platform, an entrance door from the platform to the interior of the car, exit doors from the compartments to the platform, and hand rails, dividing the platform into three ways, one for each of said entrance and exit doors.

40 10. A passenger car provided with a platform extending within the side of the car dividing the car into compartments, an entrance door from the platform to the interior of the car, exit doors from the compartments to the said platform, hand rails dividing the platform into three ways, and means forming an inclosure for the conductor near said entrance door.

45 11. A passenger car with a motorman's box at one side of the front of the car extending below the plane of the floor and to a special flooring supported at the lower edges 50 of the sills.

55 12. A passenger car having a car body with its medial line at one side of the medial line of the track gage whereby the width of the car may be increased to provide greater seating capacity.

60 Signed at Montreal, in the Province of Quebec, and Dominion of Canada, this 15 day of July, 1907.

WILLIAM GILLIES ROSS.
